US00D471635S

(12) United States Design Patent **(10) Patent No.:** **US D471,635 S**
Vogl **(45) Date of Patent:** **** Mar. 11, 2003**

(54) PACIFIER

D430,675 S * 9/2000 Roehrig D24/194
D441,083 S * 4/2001 Roehrig D24/194

(75) Inventor: **Knut Vogl**, Schwabach (DE)

FOREIGN PATENT DOCUMENTS

(73) Assignee: **Nurnberg Gummi Nip GmbH & Co. K.G.**, Georgensgmund (DE)

AT 385 411 11/1985
DE 20007609 4/2000

(**) Term: **14 Years**

* cited by examiner

(21) Appl. No.: **29/158,724**

Primary Examiner—Stella Reid

(22) Filed: **Apr. 8, 2002**

(74) Attorney, Agent, or Firm:—Hedman & Costigan, P.C.

(30) Foreign Application Priority Data

Oct. 18, 2001 (XH) DM/058 015

(51) LOC (7) Cl. **24-04**

CLAIM

(52) U.S. Cl. **D24/194**

The ornamental design for a pacifier, as shown and described.

(58) Field of Search D24/194, 193; 606/234, 235, 236

DESCRIPTION

(56) References Cited

FIG. 1 is a front elevation view of the pacifier of the present invention.

U.S. PATENT DOCUMENTS

FIG. 2 is a back elevation view of the pacifier of the present invention.

D285,839 S * 9/1986 Roehrig D24/194

FIG. 3 is a top plan view of the pacifier of the present invention; and,

D337,386 S * 7/1993 Bierend D24/194

FIG. 4 is a perspective view of the pacifier of the present invention.

D340,525 S * 10/1993 Rohrig D24/194
